UNITED STATES PATENT OFFICE

2,166,449

BASIN WRENCH

Louis Sharpe, Chicago, Ill.

Application December 27, 1938, Serial No. 247,818

3 Claims. (Cl. 81—98)

This invention pertains to improvements in wrenches, the principal object being the provision of an adjustable offset wrench for work in confined places.

5 A further object is the provision of an offset basin wrench including coacting wrench jaws shaped in a particular manner to grab any size of object between certain limits, the jaws being designed to grab or take hold simply by application of turning effort thereto in one direction.

10 A further object is an arrangement of coacting wrench jaws pivotally joined to each other with one of the jaws swiveled in a handle member for movement about an axis normal to the pivotal axis of the jaws so that the latter may be adjusted for right or left-hand action.

15 A further object is the provision of simple detent means for securing the wrench jaw assembly in a desired position of adjustment.

20 Yet another object is the provision of means coacting with the adjustment detent means for releasing the wrench head or jaw assembly for easy removal from the holder or handle, said means being further arranged for snap-action to facilitate insertion of the wrench head or jaw set into the holder.

25 Other objects, novel aspects, and economies peculiar to the invention will become apparent as the following description proceeds in view of the annexed drawing, in which:

30 Fig. 1 is a perspective view illustrating the manner of use of the novel wrench;

Fig. 2 is an end view of the wrench as it would be seen looking down in Fig. 1;

35 Fig. 3 is a fragmentary vertical section through the head of the holder or handle with the jaw assembly in elevation;

Fig. 4 is a cross section through the latch means as viewed along line 4—4 of Fig. 3;

40 Fig. 5 is an enlarged perspective cut-away view of the jaw and modified mounting and catch means;

Fig. 6 is a vertical section through the mounting means or head of Fig. 5 and illustrating the snap-in mounting of the jaw assembly; and

45 Fig. 7 is a diagram illustrative of the curvature of the coacting jaws.

The invention is of general application to interchangeable, adjustable, or demountable wrenches of all descriptions, but is particularly applicable 50 to the offset reversible jaw type of wrench illustrated in Fig. 1. This type of wrench is peculiarly adapted to working in confined spaces otherwise inaccessible to ordinary wrenches, especially, for example, beneath basins for application and re-

moval of nipples and nuts in mounting and removing water cocks and the like, as illustrated in Figs. 1 and 2.

In its preferred form, a wrench, constructed in accordance with the invention, includes a holder or handle in the form of an elongated member 10 having an enlarged head portion 11 at one end and transversely slidably handle or lever rod 12 at its opposite end.

As viewed in Figs. 2 and 3, the wrench proper 10 or jaw assembly includes a pair of cooperating jaw members 13 and 14 pivotally joined by any suitable means 15. The jaw 14 is considered a relatively stationary or mounting jaw and is provided with a mounting stud 16 which fits easily 15 into a transverse bore 17 (Figs. 5 and 6) in the handle head 11, so that the mounting jaw may be rotated about an axis transverse to the length of the handle shank. Thus, the wrench jaws may be moved into the horizontal position seen in 20 Figs. 1 and 2 (for left-hand turning) or into relatively vertical position of Fig. 3 to use the handle shank 10 as a long lever arm, or into a horizontal position reverse to that of Fig. 1 (and partly seen in Fig. 5) for right-hand turning. Intermediate 25 positions may be provided for, as will appear hereinafter.

Means for releasably securing the jaw assembly in desired positions of adjustment, includes the provision of a pin or detent 20 mounted at one 30 end in a boss 21 projecting laterally of the handle shank 10, and at its opposite end in a small bore leading transversely into the main bore 17, so that the detent pin 20 may be shifted axially back and forth in a direction parallel to the length of 35 the handle, and hence transversely into and out of the bore for the mounting stud.

The mounting stud 16 is provided with a plurality of transversely directed indentations or holes 23 (Figs. 3, 4, 6) into which the rounded 40 end or nose of the detent pin 20 may project to lock the stud against rotative movement. A spring 24 expands on the pin between the boss 21 and a cotter pin 25 and hence the detent is normally and yieldingly urged into the stud bore 45 17 for engagement in one of the holes 23 in the stud. In the embodiment of Figs. 2 and 3 the stud is prevented from working out of the bore by a cotter pin 26. By depressing a handle 22 (having an arcuated inner surface guidedly sliding against the handle 10) the nose of the detent pin may be withdrawn and the jaw member 14 rotated into a desired position corresponding to the position of one of its holes 23 in alignment with the detent. 55

When the jaw assembly is thus adjusted, it will be observed that no separation or dismounting of the parts is necessary, as was the case with prior art devices of this class.

5 In the modified arrangement of Figs. 5 and 6, a circumferential groove or track 30 is circumscribed about the stud into the holes 23, and the cotter pin 26 is dispensed with, because the detent needs only be depressed part way to withdraw the same from any notch or hole 23 to permit the stud to turn freely, the nose of the detent nevertheless remaining in the groove or track to prevent withdrawal of the stud from the bore. By depressing the detent all of the way, 15 the nose thereof will be fully withdrawn from the groove, and the stud and jaw assembly may be removed for replacement by another set of jaws or another tool.

To further facilitate the interchange of jaws 20 and tools in the holder, the studs 16 are provided with a beveled or rounded camming nose 31 which bears against the similarly rounded nose 20a of the detent and cams the latter out of the way as the stud enters the bore, the detent snapping automatically into latching engagement in 25 one of the holes 23.

An important feature of the invention is the peculiar disposition of the grasping teeth in arcuate groups arranged so that there will always be 30 at least one tooth in each jaw positioned for co-operation with a tooth in the other jaw between the limits of relative movement of the jaws.

Reference to Fig. 7 will disclose that the full line illustration of the relatively movable jaw 13 has its individual work engaging formations or teeth arranged in two contiguously arcuate groups 13a and 13b. These groups may be considered to lie in an outwardly curved work engaging surface of the jaw 13, this curved surface 40 being complex in so far as it comprises at least two curves (corresponding to groups 13a and 13b), each having its own radial center. For example, the jaw 13 in its uppermost dotted line position is arranged to illustrate the radial center for the group 13a, this center being indicated at A and it being observed that this center lies on a side of the work engaging surface or teeth toward the other jaw 14. The center for the radius of the curvature of the other group of 50 teeth 13b is illustrated in the lower dotted line position of the jaw 13 and indicated at B, and likewise it will be observed that this center B lies on a side of the work engaging surface or teeth toward the other jaw 14. Thus, the radial centers for the groups of arcuately arranged teeth in the larger or movable jaw are disposed on the same side of the teeth and on a side thereof toward the companion jaw.

It is of further importance to observe in connection with the groups of teeth 13a and 13b that the apices of the teeth of any group are directed generally toward the center of the radius of curvature for that group; this is illustrated by the terminal radii 13c and 13d extending through 65 the apices of the endmost teeth of the group 13a to converge at the center A. Stated in another way, the apices of the teeth of any group lie on the radii through the center of curvature of that group, and therefore necessarily lie in the arc 70 which subtends the angle 13c—A—13d, this angle being defined herein, and recited in the claims as the angle of inclusion of the group of teeth which it subtends. In the same manner, the group of teeth 13b lies in an arc subtending the 75

angle formed by terminal radii 13e and 13f converging in the center B.

The arrangement of the teeth in the companion or fixed jaw differs from that in the movable jaw in that the teeth lie in two arcuate groups, the centers of curvature of which lie on opposite sides of the work engaging surface. For example, one group of teeth 14a lies on an outwardly curved portion of the work engaging surface of the jaw 14 and extends from a free end 10 portion 14b of said jaw in a general direction back toward the pivotal connection 15 and merges into the oppositely or outwardly curved group of teeth 14c which extends in a general direction back toward the pivotal connection 15. 15 Thus, the work engaging surface or formation on the fixed jaw 14 is of undulatory or sinuous curvature and is curved outwardly around the free end portion of said jaw and inwardly toward the pivot point. The center of curvature 20 for the group of teeth 14a is indicated at C, and it will be observed that this center lies on an opposite side of the work engaging surface, in which the two groups lie, from the center D of the group 14c, the latter center lying on that side 25 of the work engaging surface which is nearest the other jaw 13. As in the case of the teeth of the jaw 13, the apices of the teeth in groups 14a and 14c lie on radii through the corresponding centers of curvature of their respective groups. 30

As a result of the foregoing particular arrangement of the work engaging surfaces and formations, the wrench is adapted to grasp any object which will fit between the jaws so long as a tooth or teeth of at least one group in one 35 jaw can engage the object cooperably with a tooth or teeth of at least one group in the other jaw. This may be stated in another way to the effect that the jaws will grasp an object disposed substantially therebetween when one of 40 the jaws is moved in a direction toward the other and about the object, provided the object is engaged by at least one tooth of a group in one jaw, the included angle of which includes the center of another tooth in a group in the 45 other jaw which engages the object. Viewed from still another aspect, the arrangement of the teeth in the jaws is such that in the movement of the jaws from maximum to minimum grasping relationship, there will always be at 50 least one tooth in one jaw extended in a direction to cooperate with at least one tooth in the other jaw to grasp the article.

Another advantage of the particular arrangement of the teeth resides in the ability of the jaws to engage hexagonal or square nuts with more than two points of bearing, as illustrated in Figs. 2 and 3. This is of importance in plumbing work where the wrench may be designed for certain standard fittings of this type. 55

The preferred embodiment of the invention set forth herein has been described in detail for purposes of illustration, it being understood that the objects of the invention may be accomplished by other forms and arrangements of the specific 65 means set forth, so that the invention is not to be limited to any precise details of form, location, or function except as may be exclusively provided hereinafter in the appended claims.

Having thus described my invention, what I 70 claim as new and desire to protect by Letters Patent is:

1. A wrench including pivoted jaws, one of said jaws having a mounting stud projecting therefrom normally to the pivotal axis thereof, an 75

elongated handle member provided with a transverse bore, said stud being inserted in said bore for rotative movement, a detent member mounted on said handle near said bore for movement in a 5 direction transversely into said stud, spring means normally urging said detent member into engagement with said stud, said stud having a plurality of detent engaging formations arranged circumferentially thereabout and aligned for engagement 10 with the detent member by rotative movement of the stud and jaws relative to said handle, said stud being provided with a detent track circumscribing the same through said detent engaging formations whereby said detent member may 15 be withdrawn from said detent engaging formations while remaining in said detent track to permit rotative movement of the stud and prevent withdrawal of the stud from said bore.

2. A wrench including pivoted jaws, one of 20 which is provided with a mounting stud projecting therefrom in a direction transverse of the pivotal axis of the jaws, a handle having a bore into which said stud is received for rotative movement of the same and the jaws relative to the handle, said stud 25 having a circumscribing groove thereabout, detent means mounted on said handle and yieldingly urged into said bore and into said groove in the stud, said stud having a plurality of detent locking formations disposed thereabout in said groove and 30 into which said detent means projects to lock the stud and jaws against movement relative to the handle, said detent means being withdrawn from said detent locking formations but not from said groove to prevent adjusting rotative movement of

the jaws relative to the handle, said detent means being completely withdrawn from said groove to permit withdrawal of the stud from the bore.

3. A wrench including pivoted jaws, one of 5 which is provided with a mounting stud projecting therefrom in a direction transverse of the pivotal axis of the jaws, a handle having a bore into which said stud is received for rotative movement of the same and the jaws relative to the handle, said stud having a circumscribing groove 10 thereabout, detent means mounted on said handle and yieldingly urged into said bore and into said groove in the stud, said stud having a plurality of detent locking formations disposed thereabout in said groove and into which said detent means projects to lock the stud and jaws against movement relative to the handle, said detent means being withdrawn from said detent locking formations 15 but not from said groove to prevent adjusting rotative movement of the jaws relative to the handle, said detent means being completely withdrawn from said groove to permit withdrawal of the stud from the bore, said stud having an end portion sloped to provide a camming surface, and said detent means having an inner extremity 20 normally disposed in said bore and sloped to provide a camming surface coating with the camming surface on the stud when the latter is inserted into the bore to cam said detent means out of the way, said detent means automatically 25 engaging in said groove when the latter is aligned therewith by insertion of the stud as aforesaid.

LOUIS SHARPE.
